UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,263,704.

Specification of Letters Patent. Patented Apr. 23, 1918.

Application filed January 19, 1914. Serial No. 812,975.

To all whom it may concern:

Be it known that I, LYMAN R. ROBERTS, a citizen of the United States, residing in Rutherford, in the county of Bergen and 5 State of New Jersey, have invented certain new and useful Improvements in Type-Writing Machines, of which the following is a specification.

This invention relates to a type-bar action 10 for use in writing machines.

An object of the invention is to provide an improved form of leverage-decreasing mechanism for actuating the type-bars, and in which the parts are arranged in a compact and convenient manner.

The main or key-driven levers are in the form of bell-cranks, each having an arm extending forwardly from its pivot and also an upwardly extending arm. A sub-lever 20 having an operating connection with the type-bar and pivoted at its lower end in front of an upwardly extending arm, has a rolling or shifting contact with the key lever during the type stroke, the point of 25 contact at the beginning of the stroke being remote from the pivots of the key lever and sub-lever, and gradually moving toward the pivot during the key stroke. The fulcrum of the sub-lever is above that of the key 30 lever, so that during the type stroke, said point of contact is brought comparatively close to the sub-lever fulcrum, thus accelerating the type-bar. The sub-lever may be connected through a link of thrust-rod to a 35 pivoted type-bar for throwing the latter upwardly and rearwardly against the front face of the platen.

Other features and advantages will hereinafter appear.

40 In the accompanying drawings,

Figure 1 is a sectional elevation view showing one form of the invention, the parts being in their normal position of rest.

Fig. 2 is a similar view, but showing a 45 key depressed and a type-bar thrown up to printing position, and also showing in broken lines a key and a type-bar in their normal positions of rest.

Figs. 3 and 4 are views similar to Figs. 1 50 and 2 respectively, but showing a modified construction.

The key levers 1 are shown in the form of bell-cranks fulcrumed on a rod 2 and each comprising a horizontal arm extending forwardly from the fulcrum and having a key 55

3 and an arm 4 extending upwardly from the fulcrum. In front of each arm 4 is a sub-lever 5 fulcrumed on a rod 6 and extending upwardly therefrom in position to be actuated by the arm 4. A thrust-rod or link 7 is pivoted at one end to the lever 5 and at its forward end to a type-bar 8 pivoted at 9 to a type-bar segment 10, said type-bar adapted to swing upwardly and rearwardly about its fulcrum 9 to the printing 65 position in front of the platen 11, as shown in Fig. 2.

The arm 4 of the type-bar, as shown in Figs. 1 and 2, has a shiftable connection or point of contact with the sub-lever 5, one 70 or both of the contacting faces of the levers being slightly curved so that at the commencement of the key-stroke, the upper ends of the lever 5 and arm 4 are in contact, and as the key is depressed the point of contact gradually moves downward, and at the completion of the type-stroke is near the fulcrum 6. With this arrangement a substantially uniform and even touch throughout 75 the type-stroke is provided.

At the beginning of the stroke, the point of contact being at a considerable distance from the fulcrum 6, the power applied to the key lever is effective in starting the type-bar; and during the type-stroke the point of 80 contact between the lever 5 and arm 4 moves toward the fulcrum 6 so that the ratio of the effective length of the arm 5 (that is, from the pivot 6 to said point of contact) to that of the arm 4 is decreased, so that the 85 speed of the type-bar relative to the key is accelerated.

The pivotal movement of the type-bar may be limited by a stop 12 on the segment 10 in a position to engage the type-bar when 90 the type 13 is a short distance from the platen, the resiliency of the type-bar permitting the type to be carried by momentum to the printing point. A returning spring 14 may be connected between the upper ends of 95 100 the key lever and the sub-lever 5, the ends of said levers having offset extensions 14^a to accommodate the spring. The return of the key lever may be effected or assisted by a spring 15, the upward movement of the key 105 being limited by a stop 16.

In the form shown in Figs. 3 and 4, the upper end of the arm 4 is in contact with the upper end of the sub-lever 5, but as the arm 4 swings forwardly during the type- 110

stroke a lug 17 on the arm 4 is brought into contact with the sub-lever 5 at a point a short distance above the pivot 6. After the lug 17 contacts with the sub-lever the speed 5 of the latter and consequently of the type-bar relative to the key lever is materially increased, and the upper ends of the key lever and sub-lever are gradually separated, and at the end of the stroke assume the 10 relative position shown in Fig. 4. The returning spring 14 may, as shown in Figs. 3 and 4, be connected between the link 7 and a lug 18 on the type-bar.

Variations may be resorted to within the 15 scope of the invention, and portions of the improvements may be used without others.

Having thus described my invention, I claim:

1. In a type-bar action, the combination 20 with a key lever having an arm extending forwardly from its fulcrum and an upwardly extending arm, of a sub-lever pivoted in front of said upwardly extending arm and extending upwardly from its pivot 25 and having a shiftable connection above its pivot with the upwardly extending arm of the key lever, causing the sub-lever to rotate as the key-lever rotates and in the same angular direction, and a type-bar operatively 30 connected to the sub-lever.

2. In a type-bar action, the combination of a key lever and a sub-lever each having an arm extending upwardly from its fulcrum, said arms contacting at a point above 35 and remote from both the pivots at the beginning of the key-stroke, and contacting at a point nearer both said pivots at the completion of the stroke, and a type-bar operatively connected to said sub-lever.

3. In a front-strike type-bar action, the combination with a type-bar and pivot therefor, of a key lever having an upstanding arm, a sub-lever connected to the type-bar below its pivot and in contact with said arm 45 of the key lever, the point of contact between the key lever and the sub-lever being remote from the fulcrums of both said levers at the beginning of the type-stroke and comparatively near to both said ful- 50 crums at the completion of the type-stroke, said fulcrums being so positioned that the effective length of the sub-lever relative to that of the key lever is less at the completion of the type-stroke than at the begin- 55 ning.

4. In a type-bar action, the combination with a key lever having an arm extending forwardly from its pivot and an upwardly extending arm, of a sub-lever extending upwardly from its pivot in front of said upwardly extending arm and having its pivot a substantial distance above the pivot of the key lever, a type-bar, and a connection between the type-bar and said sub-lever, said 60 sub-lever and said upwardly extending arm 65

being in contact during the type-stroke, the point of contact being above both said pivots and gradually moving downward toward said pivots during the type-stroke.

5. The combination with a bell-crank lever 70 having an arm extending upwardly from its pivot, of a sub-lever pivoted in front of said arm and extending upwardly from its pivot, a type-bar connected to said sub-lever, the upper ends of the sub-lever and said arm 75 being in contact at the beginning of a type-stroke, said arm formed to engage the sub-lever at a point adjacent its fulcrum during a succeeding portion of the type-stroke.

6. In a type-bar action, the combination 80 with a key lever having an arm extending upwardly from its pivot and swinging forwardly during the key-stroke, of a sub-lever pivoted in front of said arm and extending upwardly from its pivot and having a shifting connection with said arm during the key-stroke and swung forwardly by said arm during the key-stroke, a type-bar in front of the sub-lever, and a thrust rod connecting the sub-lever and type-bar and having a 90 forward thrust imparted thereto by the sub-lever during the key-stroke to actuate the type-bar.

7. In a type-bar action, the combination 95 with a key lever having an arm extending upwardly from its pivot, of a sub-lever also extending upwardly from its pivot, the pivot of the sub-lever being above the pivot of the key lever, said arm and sub-lever having a rolling contact during the type-stroke, the point of contact moving toward said pivots during the key-stroke, the arrangement being such that the angular speed of the sub-lever is greater than that of said key lever arm, and the outer ends of the sub-lever and 100 said arm are moved apart during the key-stroke, and a returning spring connected between said outer ends for returning said levers.

8. In a type-bar action, the combination 110 with a key lever having an arm extending upwardly from its pivot and moving forwardly during the key-stroke, of a sub-lever pivoted in front of said arm and extending upwardly from its pivot and having a shiftable connection above its pivot with said upwardly-extending arm for causing the sub-lever to rotate in the same angular direction about its pivot as the key lever rotates during the key-stroke, a type-bar 120 pivoted in front of said sub-lever, and a connection between the sub-lever and type-bar for transmitting a forward thrust from the sub-lever to the type-bar to swing the type-bar to printing position.

9. In a type-bar action, the combination 125 with a key lever having an arm extending upwardly from its pivot and having a forward movement during the key-stroke, of a sub-lever pivoted a substantial distance 130

above the pivot of the key lever and extending upwardly from its pivot in front of said arm and having a shiftable contact with said arm during the key-stroke, said sub-
5 lever being swung forwardly by said arm during the key-stroke, the point of contact between said sub-lever and arm being remote from said pivots at the commencement of the key-stroke, and comparatively near
10 said pivots at the completion of the key-stroke, a type-bar pivoted in front of the sub-lever and mounted to swing upwardly and rearwardly from a recumbent position to a printing position, and means connecting
15 the sub-lever with the type-bar at a point below the fulcrum of the latter to impart a forward thrust to the type-bar for swinging it to printing position.

10. In a type-bar action, the combination
20 with a key lever having an arm extending upwardly from its pivot and having a forward movement during the key-stroke, of a sub-lever pivoted a substantial distance

above the pivot of the key lever and extending upwardly from its pivot in front 25 of said arm and having a shiftable contact with said arm during the key-stroke, said sub-lever being swung forwardly by said arm during the key-stroke, the point of contact between said sub-lever and arm being 30 remote from said pivots at the commencement of the key-stroke, and comparatively near said pivots at the completion of the key-stroke, the ratio of the distance between said point of contact and key lever pivot to 35 the distance between said point and the sub-lever pivot being much greater at completion of the key-stroke than at the beginning, whereby the speed of the sub-lever relatively to that of the key lever is greatly increased 40 during the key-stroke.
